UNITED STATES PATENT OFFICE

117,190

DESIGN FOR A SCALE

David A. Meeker, Troy, and Kenneth C. Allen,
Dayton, Ohio, assignors to The Hobart Manufacturing
Company, Troy, Ohio, a corporation
of Ohio

Application August 9, 1938, Serial No. 79,200

Term of patent 14 years

To all whom it may concern:

Be it known that we, David A. Meeker and Kenneth C. Allen, citizens of the United States of America, residing at Troy, in the county of Miami, and at Dayton, in the county of Montgomery, respectively, and in the State of Ohio, have invented a new, original, and ornamental Design for a Scale, of which the following is a specification, reference being had to the accompanying drawings, forming a part thereof.

Fig. 1 is a perspective view of a scale from the clerk's side thereof showing our new design;

Fig. 2 is a perspective view of the scale from the customer's side thereof;

Fig. 3 is a front elevational view from the same side of the scale as Fig. 1; and

Fig. 4 is an end elevational view of the scale. The design consists of a scale having a substantially completely enclosing housing the lower portion of which is generally rectangular in shape and the upper portion of which is provided with sloping faces upon its opposite sides, with a platform supported in position closely above and generally overlying the housing, all of said parts being combined to result in the appearance substantially as shown.

We claim:

The ornamental design for a scale, substantially as shown and described.

KENNETH C. ALLEN,
DAVID A. MEEKER.
